UNITED STATES PATENT OFFICE

MAUDE T. KELLEY, OF MOUNT VERNON, NEW YORK

DESIGN FOR A WASHING APPLIANCE

Application filed May 1, 1931. Serial No. 39,685. Term of patent 14 years.

To all whom it may concern:

Be it known that I, MAUDE T. KELLEY, a citizen of the United States, residing at Mount Vernon, in the county of Westchester and State of New York, have invented a new, original, and ornamental Design for Washing Appliances, of which the following is a specification, reference being added to the accompanying drawings, forming a part thereof.

Figure 1 is a perspective view of a washing appliance, and Figure 2 is a plan view of the underside of the same appliance showing my new design.

I claim:

The ornamental design for a washing appliance, as shown.

In testimony whereof, I affix my signature

MAUDE T. KELLEY.
